UNITED STATES PATENT OFFICE.

JOHN F. TEYKL AND KENNY WAGENER, OF SMITHVILLE, TEXAS; SAID WAGENER ASSIGNOR
TO SAID TEYKL.

MEASURING DEVICE.

No. 903,143.

Specification of Letters Patent.

Patented Nov. 3, 1908.

Application filed November 30, 1907. Serial No. 404,489.

To all whom it may concern:

Be it known that we, JOHN F. TEYKL and KENNY WAGENER, citizens of the United States, residing at Smithville, in the county 5 of Bastrop and State of Texas, have invented certain new and useful Improvements in Measuring Devices; and we do hereby declare the following to be a full, clear, and exact description of the invention, such as will enable 10 others skilled in the art to which it appertains to make and use the same.

Our invention relates to new and useful improvements in measuring devices and more particularly to that class adapted to be 15 used for measuring fabrics such as embroidery, laces, or the like and our object is to provide means for measuring the fabric as it is unwound from the bolt and rewound on a cardboard or reel employed for retaining 20 the measured fabrics.

A further object is to provide means for rewinding the measured fabric onto the cardboard or reel.

A still further object is to provide means 25 for increasing or decreasing the speed of the measuring device when cards of different lengths are encountered.

Other objects and advantages will be hereinafter referred to and more particularly 30 pointed out in the claims.

In the accompanying drawings which are made a part of this application, Figure 1 is a side elevation partly in section of our improved form of measuring device and the 35 supporting standards therefor. Fig. 2 is an edge elevation thereof, showing a portion of the device in section. Fig. 3 is a sectional view as seen on line 3—3, Fig. 1. Fig. 4 is a detail sectional view on an enlarged scale of 40 the speed changing gear, and, Fig. 5 is a detail sectional view as seen on line 5—5, Fig. 3.

Referring to the drawings in which similar reference numerals designate corresponding parts throughout the several views, 1 and 2 45 indicate standards, which are preferably arranged in pairs and secured to opposite sides of base blocks 3 and 4, respectively, the upper ends of said standards being secured by means of a beam 5, which extends laterally 50 across the tops of said standards and are secured thereto in any preferred manner.

Extending laterally through the standards 1 and 2 are shafts 6 and 7, respectively, the inner ends of said shafts being provided with 55 channel plates 8 and 9, respectively, said

plates being adapted to receive the usual form of card board 10 upon which to wind the fabric 11 while the same is being measured.

The shafts 6 and 7 are rotated to wind the 60 fabric by means of a crank 12, secured to the projecting end of the shaft 6 and the shaft 7 is of sufficient length to be adjusted longitudinally through the standards to compensate for card-boards of various widths. 65

The shaft 6 has fixed thereto, between the standards 1, a gear 13, with which is adapted to mesh a pinion 14 carried by a bar 15, said bar extending at right angles to the shaft and having one of its ends rotatably mounted 70 in a supporting head 16, which is in turn pivotally mounted in a bracket 17 fixed to the inner face of one of the standards 1, a portion of the bar being square in cross section to receive a gear 18, the hub of said gear 75 likewise having a square opening to receive the bar so that said gear will be caused to rotate with the bar and at the same time move longitudinally thereon, the gear being adapted to mesh with cogs 19 on the face of a disk 80 20, said disk being rotatably mounted on the shaft 6 adjacent the gear 13, the object of movably mounting the gear 18 on the bar 15 being to increase the speed of the disk, which is accomplished by arranging the cogs 19 in 85 series from the center to a point adjacent the outer edge of the disk, said cogs being arranged to regulate the speed of the disk with the employment of card-boards of various lengths, the gear 18 being moved outwardly 90 or inwardly on the bar 15 to compensate for a shorter or longer card-board.

The various rows of cogs on the disk are numbered, so that by ascertaining the length of the card-board supported by the plates 8 95 and 9 and setting the gear 18 on the series of cogs numbered to correspond with the length of the card-board, the fabric, as it is wound on said card - board, will be accurately measured. 100

The gear 18 is moved longitudinally on the bar 15 by means of a controlling handle 21, the inner end of which is provided with fingers 22, the free ends of said fingers being bent inwardly to engage the gear 18 between the 105 rim and hub thereof, whereby the gear may readily rotate, but will be moved longitudinally on the bar by directing lateral pressure on the controlling handle.

The free end of the controlling handle is 110

extended through a slot 23 in the outer face of a casing 24 and the lower edge of said slot is provided with a plurality of notches 25, which register with the rows of cogs 19 on the 5 face of the disk 20, said notches being consecutively numbered from the outer to the inner end of the slot so that the gear 18 may be immediately set to properly measure the fabric as it is being wound on the card-board, 10 the length of the card-board being first ascertained and the controlling handle 21 engaged with the notch having the number therebelow designating the length in inches of the card-board and when the gear 18 has been 15 moved to the proper position and the handle 21 engaged with the notch at this point, said gear will be positively held in its adjusted position until the controlling handle is again raised into the slot 23.

20 When the gear 18 is to be shifted upon the bar 15, the outer end of the bar is swung laterally away from the disk, so that the gear will be out of the path of the cogs on the disk, the end of the bar protruding through a slot 25 26 in the edge of the casing 24 and is held in its inward or outward position by placing the same in notches 27 formed at each end of the slot 26.

The disk 20 is preferably five yards in circumference and the face of the disk having the cogs thereon is scaled to the yard and fractions thereof, so that as the disk is rotated, the characters on the face of the disk designating the yards and fractions thereof, 35 are brought in alinement with a window 28 formed in the outer standard 1 and, should the amount of fabric required, exceed five yards in length, a dial 29 is rotatably mounted on the outer standard 1 adjacent the upper end thereof, said dial being graduated in 40 spaces of five yards each, the periphery of said dial having spokes 30 thereon equal in number to the number of divisions on the dial, said spokes being arranged to be engaged by a pin 31, carried by the disk 20, whereby, when the disk has made a complete revolution, one of the spokes will be engaged by the pin 31 and the dial rotated, thereby indicating that five full yards have been 45 measured and the graduations on the face of the disk will indicate the fraction of yards above five yards wound upon the card-board and, as an illustration, if 11 yards are to be measured, the disk 20 is rotated until the 50 graduating mark 10 on the dial 29 and the graduating numeral 1 on the disk are exhibited through the window 28, thereby showing that 11 yards of the fabric have been wound upon the card-board employed to receive 55 the measured fabric.

60 Rotatably mounted in the upper ends of the standards 1 and 2, is a shaft 32 one end of which is provided with an auxiliary channel plate 33, which is similar to the channel plates 8 and 9 and is adapted to engage and

support a bolt of fabric and unwind the fabric from the card-board as it is being wound onto the card-board supported by the channel plates 8 and 9 and to cause the fabric from the bolt to unwind co-incident to the rewinding of the same on the opposite card-board, a sprocket-pinion 34 is fixed to the shaft 32 around which takes a sprocket chain 35, the opposite end of the chain being extended around a sprocket wheel 36 on the shaft 6, so that the card-board carried by the channel plate 33 will be rotated in unison with the card-board carried by the channel plates 8 and 9. 70 75

75 The shaft 37 on which the dial 29 is mounted is provided at its outer end with wings 38, so that the dial may be returned to its initial position or to zero after each measurement has been accomplished.

80 In applying our invention to use, a card-board is first inserted between the channel plates 8 and 9 and the length of said card-board ascertained and the gear 18 moved longitudinally on the bar 15 until it is in engagement with the proper series of cogs and secured in its adjusted position by entering the controlling handle into the notch corresponding with the cogs on the disk, thus insuring that the measuring device will properly register the length of fabric wound upon 90 the card-board. 95

95 A card-board containing a bolt of the fabric is then secured in the auxiliary channel plate 33 and the loose end of the fabric secured in any preferred manner to the card-board held in the channel plates 8 and 9, when by rotating the shaft 6, through the medium of the crank 12, the fabric will be wound onto the card-board between the standards and unwound from the bolt carried by the auxiliary channel plate 33, the fabric being guided onto the winding card-board in any preferred manner, as by the hand of the operator. 100 105

110 After the required number of yards have been wound on the card-board carried by the plates 8 and 9, said card-board is removed and an additional card-board inserted in its place, after which the measuring process may be repeated. It will thus be seen that I have provided a very cheap and accurate 115 form of measuring device and one that may be employed for measuring a variety of fabrics or similar articles and it will further be seen that the parts of the measuring device may be adjusted to accommodate receiving 120 card-boards of various lengths and widths.

125 What we claim is:

1. In a measuring device of the class described, the combination with standards, a pair of shafts rotatably mounted in said standards, means on said shafts to engage and support a card-board; of a disk rotatably mounted on one of said shafts and means interposed between said shaft and the disk to rotate said disk co-incident to the rotation 130

of said shaft, whereby fabric wound on said card-board will be measured.

2. In a measuring device, the combination with standards; of shafts rotatably mounted in said standards, one of said shafts being adjustable, means on said shafts to hold a fabric-retaining card-board, a disk loosely mounted on one of said shafts, cogs arranged in series on said disk, a bar extending at an angle from said shaft and having its inner end pivoted, means to rotate said bar and adjustable means on said bar adapted to coöperate with the cogs on the disk and increase or decrease the speed of the disk.
- 15 3. In a measuring device, the combination with standards; of shafts rotatably mounted in said standards, means carried by said shafts to support a fabric-receiving card-board, a disk rotatably mounted on one of said shafts, a gear fixed to said shaft, a bar extending at an angle to said shaft, means to pivotally anchor the inner end of said bar, a pinion on said bar adapted to mesh with said gear, cogs on the face of said disk arranged in series, a gear slidably mounted on said bar and adapted to rotate therewith, means to move said gear longitudinally of the bar and into engagement with the different series of cogs on the disk, whereby the speed of said
- 25 30 disk may be increased or decreased and additional means to anchor the gear in its adjusted position.

4. In a measuring device, the combination with standards; of shafts rotatably mounted in said standards, means on said shafts to engage and support a fabric-receiving reel, a disk rotatably mounted on one of said shafts,

cogs on one face of said disk arranged in series, a bar extending at right angles to said shaft and across the face of said disk, means 40 to pivotally mount the inner end of said bar, whereby the outer end thereof may be moved towards or from the disk, means between said shaft and bar to rotate the bar, means at the outer end of the bar to hold the same in 45 its adjusted position, a gear on said bar adapted to move longitudinally thereof and mesh with the series of cogs on the disk, a controlling handle engaging said gear and means to hold said gear in its adjusted position.

5. In a measuring device, the combination with standards; of shafts rotatably mounted in said standards, a disk loosely mounted on one of said shafts, said disk having graduations thereon, means to rotate said disk coincident to the rotation of said shafts, whereby the graduations on the disk will be brought to view, one of said standards having a window, through which said graduations may be 60 observed, a dial rotatably mounted on one of said standards and having graduations thereon in multiples of the graduations on the disk and means interposed between said disk and dial to partially rotate the dial with 65 each revolution of the disk.

In testimony whereof we have signed our names to this specification in the presence of two subscribing witnesses.
